UNITED STATES PATENT OFFICE.

JAMES D. REIFSNYDER AND HENRY G. SCHWERDTLE, OF PHILADELPHIA, PENNSYLVANIA, ASSIGNORS TO STOKES & SMITH COMPANY, OF SUMMERDALE, PENNSYLVANIA, A CORPORATION OF PENNSYLVANIA.

THROW-OUT MECHANISM FOR PRINTING-PRESSES.

1,171,804.

Specification of Letters Patent.

Patented Feb. 15, 1916.

Application filed February 26, 1914. Serial No. 821,135.

To all whom it may concern:

Be it known that we, JAMES D. REIFSNYDER and HENRY G. SCHWERDTLE, citizens of the United States, residing at Philadelphia, in the State of Pennsylvania, have invented new and useful Improvements in Throw-Out Mechanism for Printing-PresSES, of which the following is a specification.

This invention relates to rotary sheet printing presses, and particularly to an improved throw-out mechanism for arresting the operation thereof should a sheet fail to be fed thereto, and has for its principal object to provide automatic means in connection with an electrical device for separating the form and impression cylinders sufficiently to prevent an impression being made whenever a sheet to be printed fails to be fed to said cylinder by the feeding mechanism; but without stopping the rotation of said cylinders.

The invention comprises an actuating part rotating in unison with the form and impression cylinders, that, at each rotation, actuates mechanism connected to the bearings of the impression cylinder for moving the said cylinder out of printing engagement with the form cylinder, its actuation depending upon failure of a sheet to be printed being fed to said form cylinder. This mechanism is thrown into operation by an electrical device, the circuit through which is closed automatically. We prefer to provide two conductive parts in the circuit which come into contact by the absence therebetween of a sheet to be printed, thereby closing an electric circuit through a magnet which, upon being energized, connects the actuating part with the means for separating the form and impression cylinders.

The invention consists in the features and combination of features hereinafter described, all of which contribute to produce an efficient throw-out mechanism for printing presses.

A preferred embodiment of our invention will be particularly described in the following specification while the broad scope of our invention will be pointed out in the appended claims.

In the drawings: Figure 1 is a side elevation of a portion of a printing press with the invention applied thereto. Fig. 2 is a similar view with the stop mechanism in op-

erative position. Fig. 3 is an enlarged detail 55 sectional view of a portion of the feeding mechanism. Fig. 4 is a top plan view of the same. Fig. 5 is a detail view showing how the feed rollers contact to close the electrical circuit therethrough. Fig. 6 is a plan view 60 of the rotating means and mechanism operated thereby for causing the separation of the form and impression cylinders. Fig. 7 is a sectional view of the same on the line 7-7, Fig. 6. Fig. 8 is a sectional view on 65 the line 8-8 of the same figure. Fig. 9 is a cross-sectional view on the line 9-9 of Fig. 6. Fig. 10 is a diagrammatic view showing the electrical circuit for causing the operation of the stop mechanism. 70

In the drawings, 15 indicates the main frame of a printing press in the top of which are mounted a form cylinder 16, an impression cylinder 17 and a revolving take-off 18 arranged in parallel with their axes 75 lying in a common horizontal plane. The journals 19 of the form cylinder revolve in fixed bearings 20 near the rear end of the main frame 15. The journals 21 of the impression cylinder 17 turn in a journal bearing 22 on each side of the machine each of which is connected by a stiff bar 23 with a similar journal bearing 24 for the journals 25 of the rotary take-off 18. The journal bearings 22, 24 on each side of the machine which are connected by the stiff bar 23 are adapted to slide longitudinally on ways 26 on the main frame to carry the impression cylinder 17 to and from the form cylinder 16. For the purpose of moving the journal bearings and the cylinders carried thereupon, toggles 27 comprising two links 28, 29, are connected one on each side of the machine respectively with the journal bearing 24 and the main frame 15. The two links on each side are 85 pivoted together and to a vertical rod 30 which on being moved longitudinally operates the toggle and causes the journal bearings to slide on their ways 26. In the active position of the throw-out mechanism of the 90 press each toggle 27 lies in a straight line as in Fig. 1, and is prevented from moving above this position by an adjustable stop bolt 31 held immovable by a lock nut, 95 against which the top of the toggle abuts. When the rod 30 is pulled downward the toggle will assume the angular position shown in Fig. 2, whereby the journal bear-

ings 22, 24, are, with the cylinder 17 and take-off 18 drawn forward and away from the form cylinder 16 a sufficient distance to prevent an impression being made on the 5 blanket of the impression cylinder.

The rod 30 may be moved automatically, as will be hereinafter described, or manually by means of a lever 32 to which the lower end of the rod 30 is attached, said lever being fulcrumed to the main frame 15 at 33. The lever 32 is preferably made in the form of an elbow lever the shorter arm 34 of which is pivoted to one end of a normally idle link bar 35, its other end being provided with a horizontal slot 36 through which passes a cross-shaft 37 journaled in the main frame 15 and has affixed thereon a gear wheel 38 revolved by a pinion 39 on a driving shaft 40, on one end of which is a 10 hand-wheel for manually turning the same, and on the opposite end a drive pulley, not shown, or other means for imparting motion to the press. The pinion 39 also meshes with a gear wheel 42 on one end of the form 15 cylinder 16, said gear wheel being the same diameter as the gear wheel 38, and therefore rotates at the same speed and in the same direction. A gear wheel 43 on the end of the impression cylinder 17 is driven by the 20 gear wheel 42 on the form cylinder, while the take-off 18 is turned by the gear wheel 43 engaging the gear wheel 44 on the take-off shaft. The gear wheels 42, 43, and 44 are of the same diameter, and therefore the 25 three members 16, 17 and 18 rotate at equal speeds.

We are aware that mechanism for this general purpose has been employed, in which a number of parts are kept continuously in motion when the press is driven; and other parts are arranged to co-operate with this mechanism in such a way that if a sheet fails to feed into the press, a connection is made automatically from the moving 40 mechanism to the other parts which operates to separate the cylinders. In practising our invention, we prefer to provide a single moving part preferably a cam which is driven continuously when the press is being 45 driven, and near the position of this cam we provide an actuating part the movement of which by the cam imparts a force from the cam, which force separates the cylinders. In this way we simplify the mode of operation and reduce the number of moving parts. And if the single moving part is a cam, the 50 resistance to rotation of the press is the same in any position of its cylinders; in other words, there are no continuously reciprocating parts with their consequent unbalancing effects.

Mounted on the shaft 37 and turning therewith is a cam 45 more clearly shown in Figs. 6, 7, 8 and 9, against the periphery of 55 which may be moved a roller 46 mounted on

the link bar 35, and when so moved the cam pressing upon said roller pushes the link bar forward to rock the elbow lever 32 and through the connections described withdraw the impression cylinder 17 from operative engagement with the form cylinder 16. The roller 46 so long as it is in engagement with the cam 45 is held in contact therewith by a spring 47 or other suitable means which, as the cam continues to rotate causes 60 the link bar 35 to move back and forth in a straight line and the impression cylinder 17 to vibrate into and out of operative engagement with the form cylinder. The roller 46 stands normally at one side of the cam 45 and out of engagement therewith, and is only moved into position to be operated when it is desired to separate the form and impression cylinders. The means for moving the roller 46 will now be described.

Overlying the impression cylinder 17 and revolving take-off 18 is an upwardly swinging pivoted frame 48 in which is mounted a sliding feed table 49, see Fig. 3, and feed rollers 50, 51, and 52. The feed roller 51 is 70 positively driven from the gear wheel 43 on the impression cylinder through an idle gear 53 engaging a gear wheel 54 on the shaft of the roller 51. The feed roller 50 is turned by means of a rack 49^a on the sliding feed 75 table engaging a pinion 50^a on the shaft of the feed roller 50, see Fig. 3. The feed roller 52 is mounted in the outer end of a pair of arms 55 secured to a rocking shaft 56 and is moved to and from the feed roller 51 by the rocking of said shaft which has fastened on one end a telescopic arm 57 formed of two members 58 and 59 the former of which is attached to the shaft 56, and the latter slidably connected to the fixed member and movable longitudinally thereof, by means of a thumb screw 60 when it is desired to lengthen and shorten the arm. On the outer end of the member 59 is a 80 roller 62 that rests upon the periphery of a cam 63 fixed on one of the journals 19 of the form cylinder. Said cam upon each revolution of the form cylinder rocks the arm 57 and carries the feed roller 52 into and out of contact with the feed roller 51, or the 85 sheet thereon to be printed.

Bolted securely on the outer side of the link bar 35 is a solenoid magnet 64 the core 65 of which extends through the link bar and is provided on its inner end with a 90 yoke 66, the fingers of which yoke engage a groove 67 in the hub of the roller 46 that rotates freely on a stud 68 projecting inwardly from the link bar 35, and said roller can also be moved longitudinally on said stud, that it may be brought into operative 95 relation with the cam 45 or out of engagement therewith as shown in Fig. 6. The roller 46 is moved into the path of the cam 45 by the solenoid magnet 64 which when 100

the circuit is completed therethrough draws its core 65 inwardly, the yoke 66 of which slides the roller 46 into line with the cam 45, and at the proper time said cam forces 5 the roller, the link bar 35 and other parts carried thereby longitudinally as hereinbefore described in order to separate the form and impression cylinders. Upon breaking the electrical circuit through the solenoid, 10 the roller 46 is moved to the position shown in Fig. 6 by a spiral spring 69 surrounding the core between the yoke and the link bar, and the impression cylinder and the other associated parts will then be automatically 15 restored to normal position by means of the spring 47.

In order to control the circuit through the electro-magnet automatically by the sheet to be printed, we prefer to employ 20 in the electric circuit, two conductive parts which are prevented from being in contact by the sheet to be printed. In the absence of the sheet these parts come together and close the circuit. For example, this may be 25 done as follows: The sheet feed rollers 51 and 52 are both made of metal, the latter roller which is carried by the arms 55 is insulated from said arms by nonconducting 30 bearings 70, see Fig. 10. A finger 71 is in contact with the feed roller 52 or its journal, from which a wire passes to a battery or other source of electrical energy, thence to the solenoid, and from the solenoid to the feed roller 51. When the press is operating 35 and the sheets passing properly over the roller 51, the roller 52 as it vibrates to and from the roller 51 will bear on the sheet as it passes through and thus insulate the two rollers, but, should a sheet fail to be prop- 40 erly fed between the feed rollers 51 and 52 the metal roller 52 will be brought into contact with the metal roller 51, thus closing the electrical circuit through the solenoid, and the latter drawing its core inward will 45 move the roller 46 into position to be operated by the cam 45 and thus cause the impression cylinder to be moved out of contact with the form cylinder, but without stopping the rotation of either. The parts are 50 so timed that the cam 63 actuates the arm 57 to throw the feed roller 52 into engagement with the feed roller 51 only when a sheet is passing or should pass therebetween. Furthermore the cam 45 will act on the 55 roller 46 only when the form on the form cylinder is in position to contact with the impression cylinder as it revolves. Except when the cam is in substantially the position shown in Fig. 1, evidently its edge 60 projects across the end of roller 46 which would prevent the roller being moved over except at the proper time even though the circuit is closed. Inasmuch as the roller 46, is normally held out of the path of rotation 65 of the cam 45, the link-bar 35, normally re-

mains at rest and is moved only when a sheet to be printed fails to be properly fed to the printing mechanism.

In the present embodiment of the invention, it is evident that when the press is 70 running, but without having sheets fed to it to be printed, the circuit remains closed and the roller 46 runs constantly in contact with the cam, and under these conditions the spring 47 tends to move the rock-lever 75 34 toward the left and thereby holds the roller on the cam; of course, as the cam rotates it will then reciprocate the link bar 35 at every revolution. That is, at each revolution the cam throws the cylinders 80 apart, and when the gap of the cam is passing the roller, the spring 47 restores or returns the cylinders to their normal position for printing. This to and fro movement of the impression cylinders prevents 85 its face from becoming smeared with the ink on the type of the form cylinder. If this occurred, the sheets subsequently passing through the press would be smeared with ink on their rear faces. 90

It is understood that the embodiment of the invention described herein is only one of the many embodiments or forms the invention may take and we do not wish to be limited in the practice of the invention, 95 nor in our claims, to the precise embodiment described.

What we claim is:—

1. In a printing press, in combination, a 100 form cylinder, an impression cylinder mounted in bearings movable toward and from the said form cylinder to bring the cylinders into and out of coöperative printing relation, means for feeding sheets to be printed to the impression cylinder, mechanism for separating the cylinders embodying a crank having an operative connection with the impression cylinder, a normally idle reciprocatory link having a connection 105 with said crank, a rotary cam driven positively by the press when the press is in operation, a laterally movable actuating part carried by the said link and positioned adjacent to but normally out of line with the periphery of said cam, and electrically controlled means rendered operative upon the failure of a sheet to be taken by the impression cylinder, for moving the said actuating part in line with the periphery of the cam whereby the said normally idle link will be reciprocated to actuate the connections between the crank and the cylinder separating means. 115

2. In a printing press, in combination, a 120 form cylinder, an impression cylinder, mechanism for feeding sheets of paper between said cylinders to be printed upon thereby, mechanism for separating said cylinders including a laterally movable actuating part, 125 electrically actuated means for laterally

moving said actuating part, a cam driven positively by the press when the press is driven, and arranged to engage said actuating part when moved laterally and positively 5 impart a force to said mechanism and to one of said cylinders which separates the cylinders, a circuit passing through said electrically actuated means, said printing press having two conducting parts in said 10 circuit and, arranged to be separated by the sheet to be printed, whereby the absence of a sheet to be printed permits contact between said conducting parts and closes the circuit.

3. In a printing press, in combination, a 15 form cylinder, an impression cylinder co-operating therewith and adapted to be moved into and out of printing engagement with said form cylinder, said impression cylinder having movable bearings, mechanism 20 for moving said bearings to separate the cylinders including a laterally movable actuating part, electrically actuated means for laterally moving said actuating part, a cam driven positively when the press is driven and arranged to engage said actuating part when moved laterally and positively 25 impart a force to said mechanism, which force moves said bearings and separates the cylinders, a circuit passing through 30 said electrically actuated means, said printing press having two conducting parts in said circuit and arranged to be separated by the sheet to be printed, whereby the absence of a sheet to be printed permits contact between 35 said conducting parts and closes the circuit.

4. In a printing press in combination, a 40 form cylinder, an impression cylinder co-operating therewith and movable to and from said form cylinder, revolving means including a cam arranged to be continuously driven when the cylinders are rotated, said impression cylinder having movable bearings, a series of levers connected to said 45 bearings for moving the same to and from the form cylinder, an electro-magnet mounted on one of said levers and having a sliding core, a roller movable by said core when the electro-magnet is energized into engagement with said cam to operate said levers and separate the form and impression cylinders, and a circuit including a pair of 50 conductive parts adapted to be held apart by the sheet to be printed.

55 5. In a printing press, in combination, a form cylinder, an impression cylinder, mechanism for feeding sheets of paper between said cylinders to be printed upon thereby, mechanism for separating said cylinders including a laterally movable actuating part, a cam adjacent to said laterally movable part driven positively by the press when the press is driven, and normally having its edge projecting in the path of and preventing 60 the lateral movement of said movable

actuating part, electrically actuated means for laterally moving said actuating part, said cam being arranged to engage said actuating part when the same is moved laterally, and positively impart a force therethrough to said mechanism, which force separates the cylinders, a circuit passing through said electrically actuated means, said printing press having two conducting parts in said circuit and arranged to be 70 separated by the sheet to be printed, whereby the absence of a sheet to be printed permits contact between said conducting parts and closes the circuit and moves said actuating part laterally when said cam will 75 permit said lateral movement.

6. In a printing press, a sheet feeding mechanism including a pair of rollers movable to and from each other, a form cylinder, an impression cylinder driven from said form 85 cylinder at the same speed, and adapted to be moved into and out of printing engagement therewith, driving means for the form cylinder, rotating means movable by said driving means in unison with the form cylinder, and provided with a cam, means connected to the bearings of the impression cylinder for separating said cylinder from the form cylinder, and an electro-magnet device carried by said means for causing said cam 90 to operate the means and separate said cylinders when the feed rollers contact to close the circuit through the electro-magnetic device.

7. In a printing press, a sheet feeding 100 mechanism including a pair of metal rollers movable to and from each other, and forming part of an electric circuit, a form cylinder, an impression cylinder driven by said form cylinder and movable to and from the 105 same, driving means for the form cylinder, revolving means including a cam geared to said driving means and rotatable in unison with the form cylinder, a series of levers connected to the bearings of the impression 110 cylinder for moving the same to and from the form cylinder, an electro-magnet mounted on one of said levers and having a sliding core, and a roller movable by said core when the electro-magnet is energized into 115 engagement with said cam to operate said levers and separate the form and impression cylinders.

8. In a printing press, in combination, a 120 form cylinder, an impression cylinder, mechanism for feeding sheets of paper between said cylinders to be printed upon thereby, mechanism for separating said cylinders, a single moving part driven positively by the press when the press is driven, electrically 125 actuated means for causing said moving part to actuate said mechanism and impart a force thereto, which force separates said cylinders, and means for closing a circuit through said 130 electrically actuated means controlled by the

sheet to be printed, and automatic means for restoring the cylinders to their normal position.

9. In a printing press, in combination, a form cylinder, an impression cylinder, mechanism for feeding sheets of paper between said cylinders to be printed upon thereby, a lever, means actuated thereby for separating said cylinders, a cam driven positively by 10 the press when the press is driven, a link bar connected with said lever, a roller carried by said link bar and adapted to be moved into the path of said cam so as to be actuated thereby, an electro-magnet for 15 moving said roller laterally to bring the same into the path of said cam, a circuit passing through said electro-magnet, said

printing press having two conducting parts in said circuit and arranged to be separated by the sheet to be printed, whereby the absence of a sheet to be printed permits contact between said conducting parts, closes said circuit, moves said roller laterally and enables said cam to impart a force through said link bar to said lever to separate said cylinders. 20 25

In testimony whereof we have hereunto set our hands in presence of two subscribing witnesses.
